[57] ABSTRACT

On a surface of a III-V compound semiconductor substrate an Si_3N_4 layer is first deposited by a chemical vapor deposition method at a temperature between 600° and 800°C with a relatively low flow rate of SiH_4 and NH_3 , so as to have a growth rate of the Si_3N_4 layer less than about 100 Å/min. Then a phosphosilicate glass layer is deposited on the Si_3N_4 layer also by a chemical vapor deposition method. A double layer of Si_3N_4 and phosphosilicate glass thus formed serves as protective layer and/or mask for the selective diffusion, whereby such double layer avoids a warping of the substrate.

METHOD FOR MAKING III-V COMPOUND SEMICONDUCTOR DEVICES

CROSS-REFERENCE TO RELATED APPLICATION

This is a continuation-in-part application of our prior U.S. Application, Ser. No. 129,809, filed on Mar. 31, 1971 now abandoned.

BACKGROUND OF THE INVENTION

1. Field of the Invention

This invention relates to a method for making III-V compound semiconductor devices and, more particularly, to a protection layer and a diffusion mask formed on a III-V compound semiconductor substrate comprising phosphorus.

2. Description of the Prior Art

It is often a requirement that the semiconductor substrate be coated with a substance of a glass system as a mask for the protection or the selective diffusion. An SiO_2 layer has hitherto been widely used for the protective coating on the III-V compound semiconductors. For example, for the purpose of selectively diffusing zinc into a GaAs semi-conductor crystal wafer by means of an SiO_2 layer, the thickness of SiO_2 layer must be 1 to 2 μ . If the SiO_2 layer is thicker than 7,000 - 8,000 Å, there is the danger of cracking the layer due to the difference in the thermal expansion coefficient between GaAs and SiO_2 and to the intrinsic stress in the SiO_2 layer. It is known that diffusion of Ga into SiO_2 takes place in the boundary between the SiO_2 and the GaAs, thereby introducing undesirable characteristics into the semiconductor surface. When the semiconductor crystal to be coated comprises phosphorus such as GaP, $\text{GaAs}_{1-x}\text{P}_x$, $\text{In}_{1-x}\text{Ga}_x\text{P}$ and the like, SiO_2 reacts with the phosphorus contents in the semiconductor crystal to ruin the SiO_2 layer.

To solve the foregoing problems, a method of depositing a phosphosilicate glass layer of a $\text{P}_2\text{O}_5\text{-SiO}_2$ system on the semiconductor substrate has been proposed. According to this method, the phosphosilicate glass layer is formed to a thickness of about 8,000 Å which is sufficient for the purpose of the mask against zinc diffusion, thus markedly reducing the possibility of cracking the layer. Still the cracking possibility cannot totally be eliminated.

The phosphosilicate glass layer serves to detract from the surface characteristics of the semiconductor, as in the SiO_2 layer. Furthermore, the same problems as in the SiO_2 layer are unavoidable when the semiconductor crystal to be coated contains phosphorus. In other words, the phosphosilicate glass layer is usable on GaAs, but is not desirable for use on a semiconductor with phosphorus contents.

Another method proposed for improving the prior art uses an Si_3N_4 layer deposited on the substrate. This method is fairly effective in removing the foregoing drawbacks. However, for example, when an Si_3N_4 layer is formed on the whole surface of a $\text{GaAs}_{0.6}\text{P}_{0.4}$ crystal by chemical vapor deposition method, a warping of the semiconductor structure is brought about due to temperature change. Namely, the warp comes out when the heat applied to the substrate is removed after depositing an Si_3N_4 layer on the III-V compound semiconductor. This is because the Si_3N_4 and the III-V compound semiconductor have different thermal expansion coefficients; namely, $3.85 \times 10^{-6}\text{C}^{-1}$ (Si_3N_4) and 5~7

$\times 10^{-6}\text{C}^{-1}$ (III-V compound semiconductor) and because an Si_3N_4 layer deposited by a chemical vapor deposition method has a compressive or tensile intrinsic stress depending upon deposition conditions. Generally the Si_3N_4 layer tends to possess an excess of electrons and, as a result, the holes in the crystal substrate are concentrated on the surface of the semiconductor substrate. This often serves to invert the n-type crystal surface into p-type, thus forming a p-type inversion layer.

SUMMARY OF THE INVENTION

The present invention is intended for the purpose of removing all the foregoing drawbacks of the prior art by providing a novel method for depositing a protection layer or a mask on the surface of a III-V compound semiconductor substrate or on the surface of a mixed crystal of III-V compounds, and the invention is characterized in that the method comprises the steps of depositing an Si_3N_4 layer on the surface thereof at a temperature between 600° and 800°C with a relatively low flow rate of SiH_4 and NH_3 so as to have a growth rate of the Si_3N_4 layer less than about 100 Å/min. and of depositing a phosphosilicate glass layer on the Si_3N_4 layer.

By forming layers of Si_3N_4 and phosphosilicate glass in the above manner, the invention makes it possible to realize a semiconductor device in which the stress distortion caused between the layer and the semiconductor substrate is reduced, the zinc diffusion mask effect is increased, the p-n junction on the crystal surface is well protected against the atmosphere, and thus the junction characteristic is improved and the operation of the device is stabilized.

These and other objects, features and advantages of the invention will be illustrated by the following non-limitative examples taken in conjunction with the accompanying drawings.

BRIEF DESCRIPTION OF THE DRAWING

FIG. 1 is a diagram showing the state of electric charge distribution in a three-layer semiconductor element of this invention.

FIG. 2 is a cross-sectional view showing a conventional semiconductor element having its silicon substrate coated with an SiO_2 film by the thermal oxidation method.

FIG. 3 is a cross-sectional view showing another conventional semiconductor element having its substrate coated with an SiO_2 film by the chemical vapor deposition method.

FIGS. 4a through 4h illustrate the steps for producing a semiconductor device of this invention.

FIG. 5 is a cross-sectional view showing part of a semiconductor device of this invention.

FIGS. 6a through 6m show the steps for producing another semiconductor device of this invention.

FIG. 7a shows a plan view of a semiconductor device formed according to the steps shown in FIGS. 6a - 6m.

FIG. 7b is a cross-sectional view taken along line C-C' in FIG. 7a.

FIG. 8(1) is a plan view showing another semiconductor device embodying this invention.

FIG. 8(2) is a cross-sectional view taken along line A-A' in FIG. 8(1).

FIG. 8(3) is a cross-sectional view taken along line B-B' in FIG. 8(2), and

FIG. 8(4) is a partial view, on an enlarged scale, showing the structure X in FIG. 8 (1).

DESCRIPTION OF PREFERRED EMBODIMENTS

Example 1

Referring now to FIG. 1, there is shown the state of charge distribution in a three-layer structure comprising phosphosilicate glass $\text{Si}_3\text{N}_4\text{-GaAs}_{1-x}\text{P}_x$. In FIG. 1, reference numeral 11 denotes an n-type $\text{GaAs}_{1-x}\text{P}_x$ substrate, reference numeral 12 an Si_3N_4 layer, and reference numeral 13 a diffusion mask of a phosphosilicate glass layer.

As shown in FIG. 1, the effect of the double mask used for the diffusion of an impurity such as zinc is equal to the total effect of the phosphosilicate glass layer and of the Si_3N_4 layer used in the conventional manner. The double mask makes available other advantages as will appear more fully hereinafter.

The phosphosilicate glass layer tends to possess an excess of positive ions. Some Na^+ ions originate from impurities contained originally in the raw material of silicon. Some come from a small quantity of impurities during its formation, also. The layer contains, in addition, a small quantity of water which produces H^+ and silanol (Si-OH) by a reaction with silicon. Since Si_3N_4 layer ordinarily contains an excess of electrons, a double layer consisting of silicon nitride and phosphosilicate glass may be made electrically neutral. The state of electric charge distribution in the three-layer semiconductor element is shown in FIG. 1, in which $\oplus$ represents positive charge and $\ominus$ represents negative charge.

The phosphosilicate glass layer deposited on the Si_3N_4 layer by chemical vapor deposition method has a nature of modifying the foregoing warp of the semiconductor substrate caused by the Si_3N_4 layer formed independently. The thermal expansion coefficient of SiO_2 itself is very small. For example, a warp as shown in FIG. 2 is brought about when an SiO_2 layer is formed on the surface of a silicon crystal by thermal oxidation technique, and the heat applied is reduced to room temperature. Reference numeral 21 in FIG. 2 denotes a silicon crystal substrate, and reference numeral 22 an SiO_2 layer formed on the substrate 21. When this SiO_2 layer is formed by chemical vapor deposition method, the direction of the crystal warp is the reverse as shown in FIG. 3 compared to that shown in FIG. 2 due to its intrinsic tensile stress. Reference numeral 31 denotes a silicon crystal substrate, and reference numeral 32 an SiO_2 layer formed by chemical vapor deposition method. This SiO_2 layer behaves as if its thermal expansion coefficient is large. The SiO_2 layer formed on the $\text{GaAs}_{1-x}\text{P}_x$ substrate by chemical vapor deposition method behaves also as if its thermal expansion coefficient is large. That is, the direction of the warp is that shown in FIG. 3. Therefore, by suitably combining the Si_3N_4 layer with the SiO_2 layer, the warps of the two layers can be offset against each other.

A diode emitting visible light of 6,500 Å is made by using a $\text{GaAs}_{0.6}\text{P}_{0.4}$ mixed crystal and electrodes are formed directly on the light-emitting surface (p-type layer) by wire bonding technique. The production process of a light-emitting element of this invention is illustrated in FIGS. 4a through 4h. First, a 300 μ thick $\text{GaAs}_{0.6}\text{P}_{0.4}$ substrate 41 as shown in FIG. 4a is prepared. This substrate is a good crystal, formed by conventional vapor epitaxial growth technique, and has a

carrier density of $10^{16}\text{cm}^{-3} \sim 10^{18}\text{cm}^{-3}$ and a mobility of 2,000 $\text{cm}^2/\text{V.sec} \sim 3,000 \text{cm}^2/\text{V.sec}$.

For the surface treatment, the substrate is subjected to ultra-sonic washing using trichloroethylene and alcohol, pure water washing and drying by spinner. Then, the crystal substrate is placed into a chemical vapor deposition device, into which N_2 gas is supplied as the carrier gas at a flow of 151/min, and at the same time, NH_3 gas and SiH_4 gas are supplied as the reaction gases at 10 a flow of 200 cc/min and 4 cc/min, respectively. The substrate is heated up to a temperature of $600^\circ \sim 800^\circ\text{C}$. As a result thereof, an Si_3N_4 layer 42 of 1,000 $\sim$ 3,000 Å is deposited on the substrate 41 as shown in FIG. 4f according to the reaction formula $3\text{SiH}_4 + 4\text{NH}_3 \xrightarrow[600^\circ \sim 800^\circ]{\text{Si}_3\text{N}_4 \downarrow + 12\text{H}_2}$, where $\downarrow$ denotes a deposition.

The growth rate of the Si_3N_4 must be between about 10 and about 100 Å/min. Below about 10 Å/min the chemical vapor deposition process requires too long a period of time to be used in an industrial process. For the growth rates faster than about 100 Å/min, an Si_3N_4 layer obtained by chemical vapor deposition method has an intrinsic tensile stress, as discussed (for chemical vapor deposited Si_3N_4 films on silicon) by Masao Tamura et al in their article published in the Japanese Journal of Applied Physics, Vol. 11, No. 8, pp. 1097 $\sim$ 1105. Therefore, in order that the Si_3N_4 layer can compensate the aforementioned warping of an SiO_2 layer formed on a III-V compound semiconductor substrate by chemical vapor deposition method, its growth rate must be maintained at a sufficiently low value.

After this process, a phosphosilicate glass layer 43 (composition: $\text{P}_2\text{O}_5/\text{SiO}_2$ in atomic ratio $\approx 0.01 \sim 0.1$) is deposited to a thickness of 2,000 $\sim$ 6,000 Å on the Si_3N_4 layer as shown in FIG. 4c under the condition that PH_3 gas is supplied thereto at a flow of 0.7 $\sim$ 7 cc/min, SiH_4 gas at 35 cc/min, O_2 gas at 300 cc/min, N_2 gas at 51/min, and the substrate is heated to 400°C .

The phosphosilicate glass layer thus formed has an intrinsic tensile stress, as discussed by Hideo Sunami et al. in their article published in the Journal of Applied Physics, Vol. 41, No. 13, pp. 5,115 $\sim$ 5,117.

A photo-resist such as KPR and KTFR is applied to the surface of the sample to a thickness of 7,000 Å and exposed to ultra-violet rays. Then, the sample surface is developed by the use of a photoresist developer. Part of the phosphosilicate glass layer corresponding to the etching pattern determined by the photo-resist is etched by an oxide film etching solution comprising NH_4F and HF at the ratio, $\text{NH}_4\text{F} : \text{HF} = 6:1$, as shown in FIG. 4d. In this process, the Si_3N_4 layer 42 beneath the phosphosilicate glass layer is not etched by the etching solution. Then, the sample is dipped into a phosphoric acid solution held at a temperature of 180°C , thereby etching the Si_3N_4 layer with the phosphosilicate glass layer as a mask as shown in FIG. 4e. The phosphosilicate glass layer is not etched by phosphoric acid.

Then zinc is diffused into the substrate through the phosphosilicate glass - Si_3N_4 double layer. In this process, the known diffusion method using ZnAs_2 , a Ga-As-Zn or a Ga-P-Zn system is applied. The depth of the diffusion is $1.5 \sim 3\mu$ in case of a $\text{GaAs}_{0.6}\text{P}_{0.4}$ crystal. More specifically, for example, the typical diffusion condition using a Ga-P-Zn system is that 3.2 mg of Ga, 4.7 mg of P, 10.0 mg of GaP and 6.8 mg of Zn are used for the diffusion source, the diffusion temperature is about $700^\circ \sim 900^\circ\text{C}$, and the diffusion time is about

0.1~1 hour. Reference numeral 44 indicates this Zn diffusion layer. In this process, the back surface of the substrate is exposed to the diffusion atmosphere. Therefore a Zn diffusion layer 45 is formed to the same depth as in the top surface thereof, as shown in FIG. 4f. The back surface is lapped with No. 4000 carborundum, to remove the diffusion layer 45 as shown in FIG. 4g. A metal 46 such as an Au-Ge eutectic alloy, Sn, an Au-Sn eutectic alloy, an Au-Si eutectic alloy or an Ni-Au-Ge eutectic alloy which forms an ohmic contact with the n-type semiconductor is bonded to the back surface of the substrate by conventional electroless plating technique as in FIG. 4h.

The p-n junction light emitting diode alloy formed in the foregoing manner is scribed and equipped with a stem. When a forward voltage is applied to the diode, an emission of about 6,500 Å visible light is obtained from the exposed surface of the base crystal of the sample using $\text{GaAs}_{0.6}\text{P}_{0.4}$. FIG. 5 is a cross-sectional view showing the structure of a p-n junction diode fabricated in the foregoing manner. In FIG. 5, the reference numeral 51 denotes an n-type $\text{GaAs}_{1-x}\text{P}_x$ substrate, reference numeral 52 an Si_3N_4 layer, reference numeral 53 a phosphosilicate glass layer, reference numeral 54 a p-type diffusion layer into which zinc is diffused, and reference numeral 55 a back surface electrode comprising an Au-Ge eutectic alloy, Sn or the like.

Example 2

FIGS. 6a through 6m illustrate the process steps for forming a positive side electrode by evaporation technique and for providing a bonding area other than on the light emission surface. The steps shown in FIGS. 6a through 6g are the same as those shown in FIGS. 4a through 4g. After polishing the base surface of the substrate, an SiO_2 layer is formed to a thickness of 3,000 Å on the base thereof by the known technique, as shown in FIG. 6h. Then, the SiO_2 layer is photo-etched to correspond to the pattern of the electrode, as shown in FIG. 6i. Reference numeral 61 shown in FIGS. 6h through 6k indicates this SiO_2 layer. Gold is deposited to a thickness of about 3,000 Å on the SiO_2 layer by conventional evaporation technique applying base heating at 500°C, as in FIG. 6j. This Au layer is indicated by reference numeral 62 in FIGS. 6j through 6m. Instead of Au, Al may be used for the evaporated layer. If Al is used, the base heating is done at 300°C.

As shown in FIG. 6k, the Au layer, excepting for the necessary area, is removed by conventional photo-resist process using a solution prepared from 2 g of NH_4I and 0.3 g of I_2 dissolved in a solvent comprising $\text{C}_2\text{H}_5\text{OH}$ and H_2O at the ratio of 15 to 10. Then, a solution comprising NH_4F and HF at the ratio of 6 to 1 is used to remove the SiO_2 layer 61 by etching, as in FIG. 6l. One of the electrode materials, such as Au-Ge, Sn, Au-Sn, Au-Si and Ni-Au-Ge is bonded to the back surface by evaporation technique, as in FIG. 6m. Then, the sample is scribed into a plurality of separate diodes. The back surface electrode is indicated by reference numeral 63. FIGS. 7a and 7b show in plan and in sectional view, respectively, the structure of a light-emitting diode fabricated in the above manner. In FIGS. 7a and 7b, reference numeral 71 denotes an n-type $\text{GaAs}_{0.6}\text{P}_{0.4}$ mixed crystal substrate, reference numeral 72 an Si_3N_4 layer, reference numeral 73 a phosphosilicate glass layer, reference numeral 74 a p-type layer into which zinc is diffused, reference numeral 75 a window for the selective diffusion, reference numeral

76 an electrode of Al or Au, and reference numeral 77 a back surface electrode of Sn or Au-Ge.

Example 3

Applying the steps of production as illustrated in Example 2, it is possible to fabricate a photo display element having a plurality of segments. FIGS. 8(1) through 8(4) show in plan and sectional views the structure of a photo display device comprising seven segments formed according to this invention.

FIG. 8(1) is a plan view wherein segments 81, 82, 83, 84, 85, 86 and 87 are p-type layers formed on an n-type $\text{GaAs}_{0.6}\text{P}_{0.4}$ substrate 88 by selective diffusion technique. These layers are electrically isolated from each other. FIGS. 8(2) and 8(3) are sectional views taken along lines A-A' and B-B' of FIG. 8(1), respectively, wherein reference numeral 89 denotes an Si_3N_4 layer, and reference numeral 90 a phosphosilicate glass layer. The reference numerals 81', 82', 83', 84', 85', 86' and 87' represent gold or aluminum vapor deposition layers serving as electrodes for the segments 81 through 87 respectively. The electrode 85' of the central segment 85 is led out by way of an SiO_2 layer 91 by a conventional cross-over method as shown in FIG. 8(4), or through the intermediate region between segments. The back surface electrode of Au-Ge is indicated by reference numeral 92.

In summary, though Si_3N_4 is widely in use for the protection layer or mask on a GaAsP crystal substrate, its thermal expansion coefficient is smaller than that of GaAsP and it can have an intrinsic compressive stress, hence, the substrate crystal becomes warped when the heat applied to the substrate is removed after coating the protection film or mask. Although the thermal expansion coefficient of phosphosilicate glass itself is smaller than that of GaAsP, the phosphosilicate glass when formed on the substrate by a chemical vapor deposition method, behaves as if its thermal expansion coefficient is larger than that of GaAsP due to its intrinsic tensile stress. Hence, when a double layer consisting of an Si_3N_4 layer and of a phosphosilicate glass layer is deposited to a suitable thickness as a protection layer or as a mask on the GaAsP crystal substrate, it is possible to avoid the warping of the substrate. This double layer, when deposited as a protection layer or as a mask on an n-type semiconductor substrate, is advantageous also as regards the electric charge distribution.

While we have shown and described several embodiments in accordance with the present invention, it is understood that the latter is not limited thereto, but is susceptible of numerous changes and modifications as known to those skilled in the art, and we therefore do not wish to be limited to the details shown and described herein for illustrative purposes only but intend to cover all such changes and modifications as are encompassed by the scope of the appended claims.

What we claim:

1. A method for making III-V compound semiconductor devices comprising the steps of:
  - a. preparing a semiconductor substrate made of a III-V compound of first conductivity type;
  - b. depositing an Si_3N_4 layer, which is about 1,000 to 3,000 Å thick, by a chemical vapor deposition method at a temperature comprised between 600° and 800°C with a sufficiently low flow rate of SiH_4 and NH_3 so as to give a growth rate of the Si_3N_3 layer comprised between about 10 Å/min and 100 Å/min, at least partly on a surface of said substrate;

- c. depositing a phosphosilicate glass layer, which is about 2,000 to about 6,000 Å thick and in which the atomic percent ratio of P_2O_5 to SiO_2 is about 1 to about 10%, on said Si_3N_4 layer, covering substantially the whole outer surface of said Si_3N_4 layer;
- d. removing at least a part of the double layer consisting of said Si_3N_4 layer and said phosphosilicate glass layer by photoetching to thereby form a window for selective diffusion;
- e. diffusing second conductivity type impurity atoms through said window into said substrate by using said double layer as a diffusion mask, thereby forming a diffusion layer;
- f. depositing a metal layer on at least a part of the sur- 15

face of said diffusion layer within said window, thereby forming an electrode; and

- g. depositing a metal layer on the other side of said substrate, thereby forming another electrode.

2. A method for making a III-V compound semiconductor device according to claim 1, which said semiconductor substrate is of n-type and said diffused impurity atoms are of p-type.

3. A method for making a III-V compound semiconductor device according to claim 2, wherein said substrate is made of a mixed crystal of III-V compounds.

4. A method for making a III-V compound semiconductor device according to claim 3, wherein said substrate comprises P as a constituent element.
